(57) **CLAIM**

The ornamental design for an aerosol container, as shown and described.

DESCRIPTION

FIG. 1 is a perspective view of an aerosol container showing our new design;

FIG. 2 is an elevational view thereof;

FIG. 3 is a bottom plan view thereof; and,

FIG. 4 is a top plan view thereof.

The broken lines in FIGS. 1, 2, and 3 are for illustrative purposes only and forms no part of the claimed design.
